UNITED STATES PATENT OFFICE.

FREDERICK A. GOPPELT, JR., OF WATERBURY, CONNECTICUT, ASSIGNOR TO THE HOLDER MANUFACTURING COMPANY, OF WATERBURY, CONNECTICUT, A CORPORATION OF CONNECTICUT.

HOLDER FOR COLLAPSIBLE TUBES.

1,072,940.

Specification of Letters Patent.

Patented Sept. 9, 1913.

Application filed October 28, 1912. Serial No. 728,260.

To all whom it may concern:

Be it known that I, FREDERICK A. GOPPELT, Jr., a citizen of the United States, residing at Waterbury, in the county of New Haven and State of Connecticut, have invented a new and useful Improvement in Holders for Collapsible Tubes; and I do hereby declare the following, when taken in connection with the accompanying drawings 10 and the characters of reference marked thereon, to be a full, clear, and exact description of the same, and which said drawings constitute part of this application, and represent, in—

Figure 1 a side view of a holder for collapsible tubes constructed in accordance with my invention. Fig. 2 a front view of the same. Fig. 3 a broken sectional view showing the device in side view and with 20 the tube in the closed position. Fig. 4 a side view of the device with the tube inverted, and the cap in the open position.

This invention relates to an improvement in holders for collapsible tubes, and particularly for tubes of tooth paste, the object being to provide a holder for collapsible tubes in which the tube is firmly held and the outer end closed, and which permits the tube to be reversed in position for the 25 expulsion of the contents; and the invention consists in the construction hereinafter described and particularly pointed out in the claim.

In carrying out my invention, I employ 30 a suitable base 2 adapted to be secured to the wall or other convenient point. Swiveled to this base and projecting outward therefrom is an arm 3 provided at its outer end with a threaded opening 4 adapted to receive and hold the usual threaded neck 5 of a collapsible tube 6 and so that the tube 40 will be suspended from said arm. Pivotedly connected with the arm is a lever 7 carrying

at its outer end a cap 9 which may be filled with cork or other suitable material 10, and 45 which is adapted to set over the top of the neck of a collapsible tube and so as to close the open end thereof. This lever is formed at its rear end with a downwardly projecting tail 11 which bears upon a flat spring 50 12 secured to the arm. In the normal position, and as shown in Figs. 1, 2 and 3 of the drawings, the tube hangs downward from the arm and the cap closes the open end of the tube. When it is desired to expel the 55 contents of the tube the arm is rotated so that the tube will extend upward from it, as shown in Fig. 4 of the drawings. The cap may then be turned away from the open end of the tube and the contents discharged 60 onto a tooth brush. As soon as a sufficient amount has been expelled the cap will be turned to its closed position and the tube will by gravity turn the arm so that the tube again hangs downward. 65

This device provides a convenient and attractive holder for tubes of tooth paste, and closes the open end of the tube when not in use, so that the usual screw cap furnished with the tube may be discarded. 70

I claim:—

A holder for collapsible tubes comprising a base, an arm swiveled thereon and projecting outward therefrom, said arm provided at its outer end with a threaded opening 75 adapted to receive the threaded neck of a collapsible tube, a lever pivoted to said arm and provided at its outer end with a cap adapted to set over said opening.

In testimony whereof, I have signed this 80 specification in the presence of two subscribing witnesses.

FREDERICK A. GOPPELT, JR.
